CLAIM

The ornamental design for a collapsible bottom storage box, as shown and described.

DESCRIPTION

FIG. 1 is a front perspective view of a collapsible bottom storage box showing my ornamental design;

FIG. 2 is a rear perspective view thereof;

FIG. 3 is a front perspective view thereof, shown with the collapsible bottom storage box in an open configuration;

FIG. 4 is a rear perspective view thereof, shown with the collapsible bottom storage box in an open configuration;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines are included for the purpose of illustrating portions of the collapsible bottom storage box and form no part of the claimed design.
